UNITED STATES PATENT OFFICE.

MILTON RUPERT, OF PITTSBURGH, PENNSYLVANIA, ASSIGNOR TO R. D. NUTTALL COMPANY, A CORPORATION OF PENNSYLVANIA.

TROLLEY-WHEEL.

1,365,277.

Specification of Letters Patent.

Patented Jan. 11, 1921.

Application filed September 25, 1919. Serial No. 326,208.

To all whom it may concern:

Be it known that I, MILTON RUPERT, a citizen of the United States, and a resident of Pittsburgh, in the county of Allegheny and State of Pennsylvania, have invented 5 a new and useful Improvement in Trolley-Wheels, of which the following is a specification.

My invention relates to current-collecting 10 devices and particularly to trolley wheels.

One object of my invention is to provide 15 a built-up or composite trolley wheel that shall be relatively light in weight, of relatively great strength and consist of relatively few parts.

Another object of my invention is to provide 20 a trolley wheel of the above type that shall have positive means for retaining the parts in their proper relative position during the life of the wheels.

One type of trolley wheel made heretofore comprised a one-piece device of relatively soft metal such as copper. The scrapping 25 of such a wheel, after the rim had been worn down, meant the loss of considerable valuable material. Another type comprised a number of pieces such as a copper rim, with pressed steel flanges and supporting webs, requiring a relatively large number 30 of individual parts for each wheel.

In practising my invention, I provide a hub having an integral web and groove rim made of a relatively soft metal which is a good conductor, and two pressed metal 35 flanges which extend radially beyond the rim and which have a bearing on the hub to strengthen the wheel. As one of the main objects is to obtain the lowest weight consistent with the required mechanical 40 strength, length of life and conductivity, I so arrange the parts of my device as to obtain the desired results to a relatively high degree.

In the single sheet of drawings, Figure 1 45 is a side elevation of the device embodying my invention; Fig. 2 is a sectional view therethrough on the line $y-y$ of Fig. 1; Fig. 3 is a side elevation of the pressed metal flange and Fig. 4 is a sectional view 50 therethrough on the line $x-x$ of Fig. 3.

A central conducting and wearing member 1 comprises a hub 2, radial web members 3 and a grooved rim 4, these three

parts being integral and preferably made of some metal having a high conductivity. 55 The hub 2 is provided with a central longitudinal opening 5, so that it may be suitably mounted on a supporting shaft (not shown) and associated with the ordinary trolley harp. The radial web members 3 alternate 60 with a plurality of longitudinal openings 6, shown in broken lines in Fig. 1, and it will be noticed that these openings 6 are much larger peripherally than the web members 3. 65

Two pressed metal side plates 7, made of some metal possessing a relatively high strength, are used, one on each side of the member 1. Each side plate comprises a number of portions each having its own 70 particular function and these will be described in detail. The outer periphery 8 of the side plate 7 extends beyond the rim 4 and is beaded over to form a smooth outer rim. The intermediate part 9 of the plate 7 75 is shaped to contact with the side and part of the inner surface of the rim 4. The inner part of the plate 7 has two well defined peripheral portions; first those portions 10 adjacent to the openings 6, and second, those 80 portions 11 adjacent the radial web members 3. The portions 10 are so depressed or indented that their inner surfaces will contact longitudinally when the two plates are mounted on the member 1, while the 85 portions 11 are so depressed as to be adjacent to, and in contact with, the sides of the web members 3. Portions of the inner part of the side plates 7 are formed in the shape of a longitudinally extending flange 90 member 12, having an extended bearing surface on the outer periphery of the hub 2, adjacent the openings 6 and smaller portions 13, measured peripherally, adjacent the web members 3, having a relatively 95 small bearing surface on the hub 2. The two side plates 7 may be secured together by suitable means, here shown as a plurality of rivets 14, inserted in openings 15 in the depressed portions 10 of the side plates 7. 100 However, I do not wish to be restricted to the use of rivets, as I may also spot weld the two plates together at the indented portions 10. As the flange portions 12 have an extended bearing surface on the hub 2, the 105 composite trolley wheel will have ma-

terially greater strength than it would have if the whole inner periphery were formed in the shape of the portions 13.

It will also be noticed that the depressed 5 portions 10 act as a locking feature against circumferential movement of the member 1 relative to the side plates 7.

It will also be noticed that a trolley wheel constructed in accordance with my invention 10 may be relatively light in weight, yet possessing the requisite mechanical strength. Proper current conducting parts are also provided between the rim and the hub in the shape of radially extending web members 15 integral with both rim and hub, so that the side plates need not be relied upon to carry any current. The positive fastening means employed to hold the side plates together will operate to hold the side plates 20 securely in proper relative position throughout the life of the wheel.

While I have shown a specific embodiment 25 of my invention, changes may be made therein without departing from the spirit and scope of my invention, and I desire that only such limitations shall be placed thereon as are imposed by the prior art or are specifically set forth in the appended claims.

I claim as my invention:

30 1. In a trolley wheel, the combination with a grooved contact ring having integral web and hub portions, said web having a plurality of openings therethrough, of side plates contacting with said rim and extending 35 beyond the same, and having indented portions projecting into said web openings, and means for securing the side plates together and against the web and rim.

2. In a trolley wheel, the combination 40 with a hub member having a plurality of integral radially-extending web members and a rim, said web members having openings therebetween, of two side plates contacting with said rim and extending beyond the 45 same and having integral longitudinally-extending flange portions registering with and fitting into said web openings and bearing on said hub member, and rivets extending through said web openings and securing 50 the two plates together and against the web and rim.

3. In a trolley wheel, the combination 55 with a hub member having a plurality of integral radially-extending web members and a rim, said web members having longitudinal openings therebetween, of two side plates contacting with said rim and extending beyond the same and having integral longitudinally-extending flange portions 60 registering with said web openings and bear-

ing on said hub member, and means for securing said side plates together in said web openings.

4. In a trolley wheel, the combination 65 with a hub member having a plurality of integral radially-extending web members and a grooved rim, said web members having longitudinal openings therebetween, of two side plates contacting with said rim and extending beyond the same, having integral 70 longitudinally-extending flanges bearing on said hub member, the portions of said flanges adjacent to said web openings having a relatively large bearing surface on said hub, and means securing said side plates together through said web openings.

5. In a trolley wheel, the combination 75 with a hub member having a plurality of integral radially-extending web members and a rim, said web members having longitudinal 80 openings therebetween, of two side plates contacting with said rim and extending beyond the same, having integral longitudinally-extending flanges bearing on said hub member, the portions of said flanges adjacent to said web openings having a greater bearing surface on said hub than those portions adjacent the web members, and having body portions depressed into said web openings, and means for securing said side plates 85 together in said web openings.

6. In a trolley wheel, the combination 90 with a hub member having a plurality of integral web members and a rim, said web members having longitudinal openings 95 therebetween, of two side plates having a central flanged opening adapted to receive said hub, and having indented portions registering with said web openings, the flange portions adjacent to said web openings having a greater bearing surface on said hub than those portions adjacent the web members, and means for securing said indented portions of the two plates together.

7. In a trolley wheel, the combination 100 with a hub member, having a plurality of integral radially-extending arms and a rim, of two side plates having a central flanged opening adapted to receive said hub, the flange portions adjacent to the spaces between said arms having a greater bearing 105 surface on said hub than those portions adjacent the arms, and means integral with said side plates for preventing circumferential movement of said side plates on said 110 hub.

In testimony whereof, I have hereunto 115 subscribed my name this 12 day of Sept., 1919.

MILTON RUPERT.
